UNITED STATES PATENT OFFICE.

CHARLES D. JOHNSON AND PETER C. JOHNSON, OF HALIFAX, NOVA SCOTIA, CANADA.

ENGINE-PISTON.

1,252,269.

Specification of Letters Patent. Patented Jan. 1, 1918.

Application filed June 20, 1917. Serial No. 175,888.

To all whom it may concern:

Be it known that we, CHARLES D. JOHNSON and PETER C. JOHNSON, subjects of the King of Great Britain, residing at Halifax, 5 in the Province of Nova Scotia and Dominion of Canada, have invented new and useful Improvements in Engine-Pistons, of which the following is a specification.

This invention relates to engine pistons 10 and the object of the invention is to provide a piston of novel construction which will insure a thorough scavenging of the burned gases from the combustion chamber and particularly from the clearance or compression space of the combustion chamber even 15 after the exhaust stroke of the connecting rod is completed.

With the above and other objects in view, the invention consists in the novel construction, combination and arrangement of parts, 20 herein fully described, illustrated, and claimed.

In the accompanying drawings:—

Figure 1 is a sectional view taken diametrically of the improved piston and a cylinder in which the piston is mounted.

Fig. 2 is a detail view of the piston with the collar and spring removed.

Fig. 3 is a detail view of the collar.

Fig. 4 is a detail view of the spring.

Referring to the drawings 1 designates a cylinder in which the improved piston is shown as mounted to reciprocate, said cylinder being of the usual formation now 35 commonly employed in internal combustion engines.

The piston consists of two main members or sections, 2 designating what may be termed the outer section and 3 the inner section, said members or sections 2 and 3 being movable relatively to each other and having a telescopic relation to each other as clearly indicated in Fig. 1.

The outer section or member 2 of the piston 45 is provided with the usual packing rings 4 which operate in contact with the cylinder wall and said member 2 is of approximate uniform external diameter throughout. The head 5 of the piston member 2 is formed with a recess 6 in the outer surface thereof to allow clearance for the exhaust valve, where a valve in the head motor is employed. The inner piston member 3 is practically of uniform diameter 55 throughout, the lower portion of said member 3 being externally threaded as shown

at 7 to enable a collar 8 to be threaded thereon and finally secured fixedly in position thereon by means of a set screw 9 which is inserted through the section or member 3 from inside as shown in Fig. 1. 10 designates the connecting rod for the piston which is attached to the piston pin 11. This piston pin is carried by the inner section or member 3 of the piston.

The outer section 2 of the piston is formed at diametrically opposite places with slots 12 extending longitudinally thereof and therethrough which slots receive guide pins 13 carried by the inner piston member 3 and secured in relation to the latter by means of lock nuts 14. A compression spring 15 surrounds the piston member 3 and is interposed between the collar 8 and the edge 16 of the outer member 2, said spring exerting its tension to hold the piston members 2 and 3 yieldingly and normally in the position shown in Fig. 1. The face 16 against which the spring bears is preferably concaved or grooved as shown, as is also the opposing face 17 of the collar 8. The concaving or grooving of said faces or shoulders is not essential however as they may be left flat if so desired. The head 18 of the inner piston member 3 is formed with one or more compression relief vents 19 so as not to interfere with the action of the spring 15 or the movement of the heads 5 and 18 of the piston members 2 and 3 respectively toward each other.

Assuming for example that the compression of the engine cylinder and piston is seventy pounds per square inch, the collar 8 is adjusted by its threaded connection with the piston member 3 until it requires a pressure of sixty-nine pounds per square inch to force the piston 2 downwardly until the head thereof rests against the head of the piston member 3 or approaches in close proximity thereto. The members 2 and 3 of the piston should provide for a movement of the head 5 toward the head 18 sufficient to leave the ordinary compression space between the head 5 and the cylinder head. In the position of the parts illustrated in Fig. 1 it may be assumed that both piston members are starting downwardly on the suction or intake stroke. They remain in such relative positions until on the compression stroke the compression rises to seventy pounds per square inch, which pressure is more than the spring 15 will stand. Therefore the piston

2 is forced downwardly until the head thereof approaches closely to or contacts with the head of the piston member 3. During the explosion or combustion stroke, the piston members remain in the last named relative positions or in other words with the heads 5 and 18 close to or in contact with each other. During the exhaust stroke, the exhaust valves open and as soon as the pressure falls below sixty-nine pounds per square inch, the pressure of the spring 15 forces the piston member 2 upwardly and at the upper limit of the stroke of the hollow piston, the member 2 thereof reaches nearly to the top 10 of the cylinder 1, thus forcing out all or practically all of the burned gases. This of course greatly increases the power efficiency of the engine by insuring a fresh and highly combustible charge free from and unimpaired by any burned gases. Another important advantage of the invention resides in the location of the spring 15 which is far removed from the piston head 5 which is subjected to the greatest heat. The spring 20 is thus protected and is enabled to retain its resilient properties for an indefinite period of time.

We claim:—

1. An engine piston embodying two members fitting one within the other and each having a head, said members having a telescopic and slidable relation to each other, a compression spring encircling one of the piston members and bearing at one end 30 against the other piston member, and a spring holding collar surrounding the piston member which is encircled by said compression spring, said spring acting to yieldingly hold the heads of the piston members separated.
2. An engine piston embodying two members fitting one within the other and each having a head, said members having a telescopic and slidable relation to each other, a compression spring encircling one of the piston members and bearing at one end 40 against the other piston member, a spring holding collar surrounding the piston member which is encircled by said compression spring, said spring acting to yieldingly hold

the heads of the piston members separated, and means for limiting the separating movement of said heads.

3. An engine piston embodying two members fitting one within the other and each having a head, said members having a telescopic and slidable relation to each other, a compression spring encircling one of the piston members and bearing at one end against the other piston member, and a spring holding collar surrounding the piston member which is encircled by said compression spring, said spring acting to yieldingly hold the heads of the piston members separated, the head of the inner piston member being 55 60 65 vented.

4. An engine piston embodying two members fitting one within the other and each having a head, said members having a telescopic and slidable relation to each other, a compression spring encircling one of the piston members and bearing at one end against the other piston member, and a spring holding collar surrounding the piston member which is encircled by said compression spring, said spring acting to yieldingly hold the heads of the piston members separated, said collar being removable from and adjustable on the piston member which it surrounds for increasing or diminishing the 70 75 80 tension of said spring.

5. An engine piston embodying two members fitting one within the other and each having a head, said members having a telescopic and slidable relation to each other, a compression spring encircling one of the piston members and bearing at one end against the other piston member, and a spring holding collar surrounding the piston member which is encircled by said compression spring, said spring acting to yieldingly hold the heads of the piston members separated, said spring having an expansive strength slightly less than the normal compression of the cylinder in which the piston 90 95 operates.

In testimony whereof we affix our signatures.

CHARLES D. JOHNSON.
PETER C. JOHNSON.
